(57) **CLAIM**

The ornamental design for letter opener, as shown and described.

DESCRIPTION

FIG. 1 is a right side view of a letter opener showing my new design in its closed position;

FIG. 2 is a left side view thereof;

FIG. 3 is a front view thereof;

FIG. 4 is a rear view thereof;

FIG. 5 is a bottom view thereof;

FIG. 6 is a top view thereof;

FIG. 7 is a right side view of the letter opener of FIG. 1, but its opened position;

FIG. 8 is a left side view of the letter opener of FIG. 7;

FIG. 9 a front view of the letter opener of FIG. 7;

FIG. 10 a rear view of the letter opener of FIG. 7;

FIG. 11 is a bottom right isometric view of the letter opener of FIG. 1 in its closed position;

FIG. 12 is a bottom left isometric view of the letter opener of FIG. 1 in its closed position;

FIG. 13 is a bottom right isometric view of the letter opener of FIG. 1 in its opened position; and,

FIG. 14 is a bottom left isometric view of the letter opener of FIG. 1 in its opened position.

The bottom view of the letter opener of FIG. 7 is the same as in FIG. 5.
